Powell Stockhouse (875X)
Granted Patent

The invention referred to in this Patent and making part of
the same containing a description in the words of the said Powell Stock-
house himself of his improvement in the manufacture of Stoves.

This improvement on the usual construction of Stoves consists in making the flues
circular or elliptical instead of turning at one or more angles by which the heat
finds a more ready passage from the fire or furnace round the cooking chamber
box or oven of the stove and imparts to it a greater degree of heat more uni-
formly diffused than by any previous invention. To construct a stove ac-
cording to this improvement the plates of the stove enclosing the flue or
flues must be made or cast in a circular or elliptical form connecting
one end with the fire or furnace and the other with the pipe or upper
chamber with which the pipe connects and the flue or flues may pass up
either in the rear front or sides of the stove and the latter mode is practised
by this inventor. This improvement may be useful in a stove for burning kind
of fuel by the greater economy in oil or gas or in burning coal especially so in
cooking stoves to be heated by anthracite coal. The more equal diffusion
of heat round the oven performing more equally on all sides the operation
of cooking baking &c. Witness my hand this 3rd day of December 1831
